CLAIM

I claim the ornamental design for a solar address light, as shown and described.

DESCRIPTION

FIG. 1 is a perspective view of the solar address light showing the new design;

FIG. 2 is a front elevational view thereof;

FIG. 3 is a rear elevational view thereof, the right side and left side elevational views being identical images thereof;

FIG. 4 is a top plan view thereof; and,

FIG. 5 is a bottom plan view thereof.

The dotted lines are for illustrative purposes only and form no part of the claimed design.
